(57) **CLAIM**

The ornamental design for a soft kettle bell, as shown and described.

DESCRIPTION

FIG. 1 is a front view of a soft kettle bell of the present invention, the opposing rear view being a mirror image thereof;

FIG. 2 is a side view of a soft kettle bell of the present invention, the opposing side view being a mirror image thereof;

FIG. 3 is a top view of a soft kettle bell of the present invention;

FIG. 4 is a bottom view of a soft kettle bell of the present invention; and,

FIG. 5 is a front perspective view of a soft kettle bell of the present invention.

The broken lines showing a number illustrate environmental structure which forms no part of the claimed design.

It is understood that the broken lines forming an "X" within a square shape, indicate stitch lines which forms part of the claimed design.
